UNITED STATES PATENT OFFICE.

JOSEPH LYON, OF DAYTON, OHIO, ASSIGNOR TO FRANK J. McCORMICK, TRUSTEE, OF DAYTON, OHIO.

BURGLAR-ALARM WINDOW-FASTENER.

SPECIFICATION forming part of Letters Patent No. 764,534, dated July 5, 1904.

Original application filed August 14, 1901, Serial No. 71,877. Divided and this application filed June 10, 1903. Serial No. 160,909. (No model.)

To all whom it may concern:

Be it known that I, JOSEPH LYON, a citizen of the United States, residing at Dayton, Montgomery county, Ohio, have invented a certain new and useful Burglar-Alarm Window-Fastener, of which the following is a specification, reference being had to the accompanying drawings, forming a part hereof, and in which like characters of reference indicate the same parts, said invention being a part of my application, Serial No. 71,877, filed August 14, 1901, for a burglar-alarm house-protector and being now divided therefrom.

My invention relates to improvements in burglar-alarm window-fasteners; and it consists of the means, combinations, arrangements, and subcombinations of the various parts and means, all as hereinafter described at length and briefed in each of the appended claims.

The means best known to me at this time for accomplishing the objects of my invention are illustrated in the accompanying drawings, in which

Figure 1 is an elevation view of a portion of the upper and lower sash and their casing, a portion of the casing being broken away to disclose the parts within. Fig. 2 is a sectional plan view substantially on line $x-x$ of Fig. 1. Fig. 3 is a side view of one of the window-locking bolts in section substantially on line $x-x$ of Fig. 2. Fig. 4 is an elevation view, partially in section substantially on line $y-y$ of Fig. 1. Fig. 5 is an interior view of a portion of a house adapted to be protected and rendered burglar-proof by my invention. Fig. 6 is a sectional view from the left of Fig. 1 and omitting the alarm-bolt and its mounting mechanism. Fig. 7 is a sectional view of a portion of the meeting-rails of the sash and showing the ordinary window-fastener.

The house or structure to be protected may have any desirable number of windows or openings adapted to be closed by a plurality of slidable members, each of which is provided with the following means: Upon the top of the lower sash 50 or near the meeting edge of one of said slidable members is se-

cured a bearing-plate 51, upon which is slidably mounted in any suitable manner a plate 50 or bolt 52, provided with projections 53, to which is pivotally connected a supplemental bolt 54 at a point intermediate its ends, said supplemental bolt 54 having two branches projecting at an angle to each other and said pivoted connection of said supplemental bolt 54 being intermediate said branches. The branch 47 of said supplemental bolt 54 projects laterally therefrom and is adapted to co-operate with any one of a plurality of keepers 60 mounted upon the inner face of the upper sash 55, while the branch 48 of said supplemental bolt 54 projects therefrom with its longitudinal axis parallel with the slidable movement of said bolt 52 54 and is adapted 65 to enter any one of a plurality of keepers mounted upon the window-casing 60 adjacent said bolt.

The keepers upon the upper sash 55 are formed of a plurality of projections or pins 56, 70 removably secured to the inner edge of the upper sash 55 and projecting therefrom to substantially the height of the ledge 61 upon the bottom of said upper sash 55. Said projections 56 may be upon the upper and lower 75 sides of the bolt branch 47 to constitute each keeper, as shown for the upper keepers upon the upper sash, or but one projection 56 upon the upper side of the bolt branch 47 may constitute each keeper upon the upper sash, as 80 shown for the lower keeper upon said upper sash.

Each of the keepers upon the casing 60 is formed of a face-plate 62, having a keeper-opening 63 therein, Figs. 1 and 6, said opening 63 being larger than said bolt 52 54 in a vertical direction—that is, in the direction of the movement of the lower sash 50. Secured to and projecting from the rear side of plate 62 are plates 64 and 65 at an angle to each 90 other and extending into an opening 66 in the casing 60. Secured to said plate 64 is an electrical contact member 67, insulated from said plate 64, while secured to said plate 65 is an electrical contact member 68, having a projection 69 adapted to normally engage or con-

tact with said member 67 for normally maintaining an electrical circuit. Members 67 and 68 are substantially at right angles to each other, and member 68 is uninsulated from said plate 65 and plates 64 and 65 being integral or electrically connected together. Member 67 is mounted above the plane of the keeper-opening 63, and below said member 67 is an electrical contact member 70, having a projection or downward bend 71 extending into the plane of said keeper-opening 63 and adapted to engage with the branch 48 of bolt 54 and be moved thereby into contact with member 67 for the purpose of establishing an electrical circuit, member 70 being secured to plate 64 by screw 72, which also secures member 67 thereto, said member 70 being insulated from said member 67, which member 67 is also insulated from said plate 64 by the insulation-disks shown. Electric-circuit wires 73 and 74 connect, respectively, with members 68 and 67, the circuit being normally closed by projection 69 of member 68 contacting with member 67. The outer end of member 68 projects into the plane of the keeper-opening 63, Figs. 4 and 6, and is curved at its outer end, (see Fig. 2 in dotted lines,) so that when the bolt 52 54 is shot into its keeper 93 it will be engaged along its side by member 68, and the curved or cam-shaped end of member 68 will cause said bolt to move said member 68 laterally and separate its projection 69 from member 67, and thus break the electrical circuit. The outer end of plate or bolt 52 is provided with an upturned outer end 75, adapted to enter the keeper-recess 63 and contact with the members 68 for keeping its projection 69 out of contact with member 67. The lateral or sliding contact on the bolt of the members 68 and 70 dispenses with nicety, exactness, and uniformity in the shooting of the bolt and provides a safe contact unaffected by wear upon the parts or careless operation.

Should bolt 52 54 be withdrawn from its keeper-opening 63 at any time, the projection 69 will by the withdrawal more especially of the keeper end of bolt member 52 be moved into contact with electrical contact member 67 by reason of the spring contact member 68 assuming its normal position in the plane of said keeper-opening 63, and an electrical circuit will thereby be established.

While bolt 52 54 is in its keeper-opening 63, should an entrance be attempted by lowering the upper sash 55 one of the projections 56 will be pressed downward upon the branch 47 of bolt member 54, which will cause the branch 48 of bolt member 54 within said keeper-opening 63 to be raised vertically and contact with the downward projection or bend 71 of the spring contact member 70 and move said member 70 into engagement with electrical contact member 67, thereby establishing an electrical circuit between the members 67 and 70 through member 68, while if the

lower sash 50 be raised to force an entrance the bolt 54 will be moved upward at its outer end 48 by reason of the fulcrum of said bolt 54 and its engagement at its opposite end 47 with one of the projections 56 of the upper sash, which movement of said bolt 54 will likewise move member 70 into engagement with member 67 and similarly establish an electrical circuit. Each of the members 67 within each of said keeping-openings 63 forms one circuit-terminal, while the opposite or other circuit-terminal is branched and is composed of the members 68 and 70, either of which is adapted to be brought into engagement with the members 67, according to the movements of bolt 52 54.

Should entrance be attempted by removing a portion of the glass and withdrawing bolt 52 54 preparatory to raising the sash 50 or lowering the sash 55 preliminary to entrance, the withdrawal of bolt 52 54 will establish an electrical circuit between members 68 and 67, as heretofore stated.

The keepers in the frame or casing 60 of each window are uniform distances apart, while the keepers upon the upper sash 55 are preferably the same uniform distances apart in order to provide for ventilation by lowering the upper sash or raising the lower sash, or both, desirable distances and locking them in said position with my improved burglar-alarm window-fastener simply by the shooting of a bolt for each window.

The keeping-openings 63 in each window-casing 60 are near the upper sash 55 in order to permit their respective bolts 52 54 to enter upon one side of the sash-cord 80 for each of the lower sash 50.

The contact members 67, 68, and 70 of each of the plurality of keeping-openings 63 for each window are adapted to and compose a single circuit with the annunciator 81 and battery or other electrical generator 82 and bell or alarm means 83, and each window is connected thereto by a separate circuit, so that each opening where an entrance is attempted to be effected may be indicated by the annunciator 81.

In the instance shown in the drawings the plate 51 is secured to the sash 50 by a plurality of screws 85, while the bolt 52 is slidably mounted thereon by screws 86, passing through slots 87 in said bolt 52 and embedded into plate 51, said bolt 52 being adapted to be locked in either position out of its keeper-opening 63 by means of a screw 89, adapted to clamp bolt 52 to said plate 51.

Bolt 54 is provided with a cylindrical cavity 90, containing a cylindrical pin 91, preferably of hardened steel, loosely fitting said opening 90 and being loosely sealed in said opening by a plug 92, closing the mouth of said opening 90 for the purpose of preventing an opening being forced without giving an alarm by sawing off the bolt 54 and leaving the end or branch 130

48 thereof in one of the keeping-recesses 63, so that an entrance may be effected thereby without giving the alarm. Should bolt 54 be attempted to be sawed, the saw will go through 5 the outer surface of bolt 54 and penetrate a portion of the cavity 90 and contact with the pin 91, and the saw will roll pin 91, and consequently the saw can gain no hold upon said pin 91, and therefore the saw will be effectually resisted and prevented from sawing through the bolt 54. Of peculiar importance is this feature, together with that of the elongation of opening 63 to permit only a limited movement of said bolt and the sash in the direction of the travel of the window - sash, whereby an alarm is sounded while entrance is effectually barred by the bolt 52 54; thus giving the occupants of the house protected by my invention ample opportunity to summon aid or otherwise prepare to resist such an invasion before an entrance is effected.

Mounted centrally upon the meeting-rails of each of the upper and lower sashes 50 to 55 is the ordinary window-fastener, comprising a keeper 100, having keeping-opening 101 adapted to snugly fit bolt 102, movably mounted in casing 103 and adapted to be actuated by lever 104, said ordinary window-fastener being within view from the outside and being deceptive to the extent that it renders an intruder less cautious and to believe that said ordinary window-fastener 100 to 104 is the only securing device for each window; and a further primary object of said ordinary window-fastener is that when each window is closed the locking of each window by means of said ordinary window-fastener, in addition to locking the same with the bolts 52 54, prevents the sounding of an alarm by the relative movement of the bolts 52 54 in their respective keepers, as aforesaid, until said ordinary window-fastener is either badly sprung or is broken by the attempt of an intruder to cause an entrance. Said ordinary window-fastener may be of any of the common constructions employed.

It will be seen that with the means or apparatus preferably employed for the purpose of practicing or exemplifying my invention, 50 which means or apparatus may be departed from in many respects without departure from the spirit and scope of my invention, each of the windows when locked in any of their ventilating positions is most conveniently set for sounding an alarm by having the end 75 of bolt 52 engaging the bottom of its its keeping-opening 63, and a very slight relative movement of either the sash or keeper will sound an alarm, while entrance is yet barred by the bolt 52 54 in its keeping-opening 63 for each window.

Spring 110 between bolts 52 and 54 causes bolt 54 to engage bolt 52 at its end 48 under normal conditions and prevents an alarm 65 from being sounded by the vibration of bolt

54 upon its fulcrum, due to slight jars upon the windows, due to causes other than attempts to open the windows.

Having now so fully described my invention that others skilled in this art may freely 70 make and use the same when this exclusive grant shall cease to operate, what I claim, and desire to secure by Letters Patent, is—

1. The combination of a window - sash mounted in a window-casing, a bolt movably 75 mounted upon said sash, a keeper mounted in said casing for said bolt, said keeper having keeping-opening wider than said bolt in the direction of the movement of said sash, a member mounted in said keeper normally in 80 the path of said bolt when shot into said keeper, a second member mounted in said keeper adjacent said first member, said first and second members being adapted to engage with each other when said bolt is withdrawn 85 from said keeper and when said sash is moved, means for sounding an alarm upon the engagement of said first and second members, and a second bolt and keeper for said sash, whereby when said first bolt is tampered with 90 an alarm is sounded by said first bolt and said first and second members and the house is protected by said second bolt and keeper, substantially as specified.

2. The combination of a bolt member 52, 95 a second bolt member 54, means whereby said bolt members may be shot in unison, and one of said bolt members may be moved in a direction at an angle to said shooting movement of said bolt members, keepers for said bolt 100 members, alarm means extending into the paths in which each of said bolt members are adapted to be moved, said alarm means being adapted to be actuated upon any movement of said bolt members, a member upon which 105 said bolt members are supported, a second member upon which said keepers are mounted, and a third member adapted to engage said second bolt member, said bolt members being relatively movable upon the relative 110 movement of any two of said three members, substantially as specified.

3. The combination, in a fastening and circuit-closing device, of a pivoted bolt mounted to slide upon a movable member or window-sash, means carried upon another movable member or window-sash to engage and rock said pivoted bolt, a bolt-keeper mounted in a relatively stationary member or window-casing and carrying contacts in the path of the 115 bolt and operating to close an electrical circuit when the bolt moves with its movable member, or when it is rocked on its pivot, and when it is slid or withdrawn from its keeper.

4. The combination of a window-sash, a casing therefor, a bolt movably mounted upon said sash, a keeper for said bolt mounted in said casing, a member mounted to one side of said bolt and having a cam-shaped end pro- 120 125 130

jecting into the path thereof when shot into said keeper, said member extending substantially parallel with said bolt and said cam-shaped end of said member slidably engaging 5 one side of said bolt substantially throughout its shooting movement, a second member normally in engagement with said first member, but disengaged therefrom when said bolt is in said keeper, and means for sounding an alarm 10 upon the engagement of said first and second members, substantially as specified.

5. The combination of a movable member, a second member, a bolt carried by one of said members and a keeper carried by the other of 15 said members and into which said keeper said bolt is adapted to be shot at an angle to the plane of movement of said movable member, said bolt also having a limited movement in its keeper in the direction of the movement 20 of said movable member, and alarm-sounding means projecting upon that side of said bolt adapted to resist the movement of said movable member and into the path of and adapted to be operated by said limited movement of 25 said bolt, said alarm-sounding means being adapted to engage the side of said bolt when said limited movement is imparted to said bolt, substantially as specified.

6. The combination of a movable member, 30 a second member, a bolt carried by one of said members and a keeper carried by the other of said members and into which said keeper said bolt is adapted to be shot at an angle to the plane of movement of said movable member, 35 said bolt also having a limited movement in its keeper in the direction of movement of said movable member, and a pair of circuit-closing contacts one of which said contacts projecting upon that side of said bolt adapted 40 to resist the movement of said movable member and into the path of and adapted to engage the side of said bolt and be operated by said limited movement of said bolt when in its keeper, substantially as specified.

45 7. The combination of a window-sash, a casing therefor, a bolt carried by one of said members, and a plurality of keepers each at a different height and carried by the other of said members, said bolt being adapted to be 50 shot into any of said keepers, said bolt also having a limited movement in any of said keepers at an angle to said bolt, and a plurality of pairs of circuit-closing contacts, one of each pair being in the path of and adapted to 55 be operated by said limited movement of said bolt at each keeper, substantially as specified.

8. The combination of a movable member, a casing therefor, a bolt carried by one of said members and a keeper therefor carried by the 60 other of said members, said bolt having a limited vertical movement in its keeper, alarm-sounding means in the path of and adapted to be operated by said limited movement, and a second bolt and keeper for retaining said movable member, substantially as specified.

9. The combination of a movable member, a casing therefor, a bolt carried by one of said members and a keeper therefor carried by the other of said members, said bolt having a limited vertical movement in its keeper, a pair of circuit-closing contacts in the path of and adapted to be operated by said limited movement, and a second bolt and keeper for retaining the said movable member, substantially as specified. 70

10. The combination of the window-sash and its casing, a bolt carried by one of said members, a plurality of keepers for said bolt carried by the other of said members, said bolt having a limited vertical movement in each of 80 said keepers, alarm-sounding means in the path of and adapted to be operated by said limited movement, and a second bolt and keeper for said sash, substantially as specified.

11. The combination of the window-sash 85 and its casing, of a bolt carried by one of said members, a plurality of keepers for said bolt carried by other of said members, said bolt having a limited vertical movement in each of said keepers, a pair of circuit-closing contacts 90 in the path of and adapted to be operated by said limited movement, and a second bolt and keeper for said sash, substantially as specified.

12. The combination of the window-sashes, 95 a casing therefor, a bolt mounted upon one of said sashes, a keeper therefor carried by said casing, said keeper having a recess for said bolt larger than said bolt, in the direction of the opening movement of said sash, a second and third member normally out of engagement with each other and mounted adjacent said keeper and normally out of engagement with said bolt when shot into said keeper, said third member being in the path of movement of said bolt when the sash is attempted to be 100 opened, whereby said third member is moved into engagement with said second member, and means for sounding an alarm upon the engagement of said second and third members, 105 substantially as specified.

13. The combination of two window-sashes, a casing in which said sashes are mounted, a bolt movably mounted upon one of said sashes, a supplemental bolt fulcrumed upon said sliding bolt, a plurality of keepers for said supplemental bolt carried by said other sash, a second keeper for said supplemental bolt carried by said casing, separated portions of said supplemental bolt having portions adapted to enter any one of said first keepers and said second keeper, a second and third member carried by said casing, one of which said members being in the path of the pivotal movement of said supplemental bolt, whereby upon the relative movement of said sash said supplemental bolt moves said members into engagement with each other, and means for sounding an alarm upon the engagement of said second and third members, substantially as specified. 115 120 125 130

14. The combination of a window-sash, a casing therefor, a bolt movably mounted upon said sash, a supplemental bolt mounted upon said sliding bolt, keepers for said supplemental bolt mounted upon said other sash, a second keeper for said supplemental bolt mounted upon said casing, a member mounted to one side of said bolt and in the path thereof when shot into said second keeper, a second member normally in engagement with said first member, but disengaged therefrom when said bolt is in said keeper, said second member being out of the path of said bolt, a third member normally out of the path of said bolt and intermediate said bolt and said second member, said bolt being adapted to force said third member to engage with said second member when said sash is moved a limited distance in an attempt to open the same, and means for sounding an alarm upon the engagement of either of said first and third members with said second member, substantially as specified.
15. The combination of a window-sash, a casing therefor, a bolt movably mounted upon said sash, a supplemental bolt mounted upon said sliding bolt, a plurality of keepers for said supplemental bolt mounted at different points upon said other sash a second keeper for said supplemental bolt mounted upon said casing, a member mounted to one side of said bolt in the path thereof when shot into said second keeper, a second member normally in engagement with said first member, but disengaged therefrom when said bolt is in said keeper, said second member being out of the path of said bolt, a third member normally out of the path of said bolt and intermediate said bolt and said second member, said bolt being adapted to force said third member to engage said second member when said sash is moved a limited distance in an attempt to open the same, and means for sounding an alarm upon the engagement of either of said first and third members with said second member, substantially as specified.
16. The combination of a window-sash, a casing therefor, a bolt movably mounted upon said sash, a supplemental bolt mounted upon said sliding bolt, a plurality of keepers for said supplemental bolt mounted at different points upon said other sash, a plurality of second keepers for said supplemental bolt mounted at different points upon said casing, a plurality of members mounted to one side of said bolt and in the path thereof when shot into said second keeper, a plurality of second members normally in engagement with said first members, but disengaged therefrom when said bolt is in said keeper, said second members being out of the path of said bolt, a third plurality of members normally out of the path of said bolt and intermediate said bolt and said second members, said bolt being adapted to force any of said third mem-
- bers to engage with its said second members when said sash is moved a limited distance in an attempt to open the same, and means for sounding an alarm upon the engagement of either of said first and third members with said second members, substantially as specified.
17. The combination of the window-sashes, a casing therefor, alarm means, and means carried by one of said sashes and adapted to engage said other sash and a portion of said alarm means whereby said alarm means is actuated upon the movement of either of said sashes substantially as specified.
18. The combination of the upper and lower window-sashes, means for simultaneously locking both said sashes and permitting a limited movement thereof when locked, and means in the path of and adapted to be actuated by said limited movement whereby an alarm may be sounded by said limited movement of either of said sash while locked, substantially as specified.
19. The combination of a plurality of window-sashes, a casing therefor, means for locking said sashes at one point to said casing and permitting a limited movement of said sashes while locked, and means whereby an alarm may be sounded upon the movement of any of said sash while locked, substantially as specified.
20. The combination of a window-sash, a casing therefor, a keeper carried by one of said members and a bolt carried by the other of said members, the keeping-opening of said keeper being wider in said bolt in the direction of the movement of said sash, a second bolt mounted upon the window-sash, a keeper for said second bolt having a keeping-opening substantially no wider than its bolt in the direction of the movement of said sash, and means whereby an alarm may be sounded by any relative movement of one of said bolts in its keeper, substantially as specified.
21. The combination of a window-sash, a casing therefor, a keeper carried by one of said members and a bolt carried by the other of said members, the keeping-opening of said keeper being wider than said bolt in the direction of the movement of said sash, and means located upon one side of said bolt when in said keeping-opening whereby an alarm may be sounded by the movement of the sash while locked by said bolt and keeper, substantially as specified.
22. The combination of a window-sash, a casing therefor, a keeper carried by one of said members and a bolt carried by the other of said members, the keeping-opening of said keeper being wider than said bolt in the direction of movement of said sash, an electrical circuit, and means for making or breaking said electrical circuit by the movement of the sash while locked by said bolt and keeper, said means being located upon one side of said

bolt when said bolt is in said keeping-opening, substantially as specified.

23. The combination of a window, a casing therefor, a plurality of keepers carried by one of said elements, a bolt carried by the other of said elements, the keeping-openings of said keepers being wider than said bolt in the direction of movement of said window, an electrical circuit, and means whereby said circuit

10 is made or broken by any relative movement of said bolt and any of said keepers, substantially as specified.

24. The combination of a window, a casing therefor, a plurality of keepers carried by one 15 of said elements, a bolt carried by the other of said elements, the keeping-openings of said keepers being wider than said bolt in the direction of movement of said window, and means whereby an alarm may be sounded upon 20 the relative movement of said bolt in any of said keepers, substantially as specified.

25. The combination of a plurality of relatively movable members, a casing therefor, keepers carried by said casing and one of said 25 members, one of said keepers having a keeping-opening relatively wide in the direction of movement of said members, means carried by the other of said members and adapted to engage said keepers, and alarm apparatus 30 adapted to be actuated upon the relative movement of said means and said keeper having said wide opening, substantially as specified.

26. The combination of a plurality of relatively movable members, a casing therefor, 35 keepers carried by said casing and one of said members, one of said keepers having a keeping-opening relatively wide in the direction of movement of said members, a bolt carried 40 by the other of said members and having projections adapted to engage said keepers, and alarm apparatus adapted to be actuated upon the relative movement of said bolt and said keeper having said wide opening, substantially 45 as specified.

27. The combination of a plurality of relatively movable members, a casing therefor, keepers carried by said casing and one of said 50 members, one of said keepers having a keeping-opening relatively wide in the direction of movement of said members, a fulcrumed bolt carried by the other said members and having projections upon opposite sides of said fulcrum adapted to engage said keepers, and 55 alarm apparatus adapted to be actuated upon the relative movement of said bolt and said keeper having said wide opening, substantially as specified.

28. The combination of a movable member, a second member, a fulcrumed bolt slidably supported upon one of said members, a keeper therefor carried by the other of said members, said bolt being movable into and out of said keeper, and alarm means in the path of that portion of said bolt separated by said fulcrum from the portion of said bolt kept by said keeper, substantially as specified. 60 65

29. The combination of three members, a fulcrumed bolt slidably supported upon the first member, a keeper therefor carried by the 70 second member, said bolt being movable into said keeper and toward said third member, said bolt being fulcrumed intermediate its ends and said keeper keeping one end only of said bolt, and alarm means carried by said third member in the path of the remaining end of said bolt when said bolt is kept by said keeper, substantially as specified. 75

30. The combination of two relatively movable members, a portion movably supported 80 upon one of said members, a bolt pivotally connected to said portion, a keeper carried by said other member and into which keeper said bolt is adapted to be shot, and alarm means in the path of the pivotal movement of said bolt 85 when said bolt is in said keeper, substantially as specified.

31. The combination of two relatively movable members, a portion movably supported upon one of said members, a keeper carried 90 by the other of said members, a bolt pivotally connected to said portion and adapted to be shot into said keeper, and a pair of circuit-closing contacts, one of which said contacts being in the path of the pivotal movement of 95 said bolt when in said keeper, substantially as specified.

32. The combination of a bolt, a movably-supported member pivotally connected to said bolt at a point intermediate its ends, a keeper 100 for each of the opposite ends of said bolt, one of said keepers having its keeping-opening wider than said bolt in a direction at an angle to the direction in which said bolt is adapted to be shot, and contact members adapted to 105 be operated by said bolt, substantially as specified.

In testimony whereof I have signed my name to this specification, in the presence of two subscribing witnesses, this 3d day of January, 110 1903.

JOSEPH LYON.
